UNITED STATES PATENT OFFICE.

KARL HUTTER, OF NEW YORK, N. Y.

BOTTLE-STOPPER.

SPECIFICATION forming part of Letters Patent No. 562,225, dated June 16, 1896.

Application filed February 18, 1896. Serial No. 579,730. (No model.)

To all whom it may concern:

Be it known that I, KARL HUTTER, a resident of the city, county, and State of New York, have invented certain new and useful 5 Improvements in Bottle-Stoppers, of which the following is a specification.

My invention relates to bottle-stoppers, and has for its object to produce a bottle-stopper which will constitute a "double-seal" stopper 10 which will contain a minimum of elastic material and will require a minimum amount of pressure to seat it in the bottle. I will explain that by a double-seal stopper I mean one which will seal both the neck and the mouth 15 or lip of the bottle.

In setting forth my invention I will have reference to the accompanying drawings, and will now proceed to point out and claim the novel features of my stopper.

20 In the drawings, Figure 1 is a section through a bottle-neck, showing my stopper in position above the mouth of a bottle and about to be entered thereinto. Fig. 2 is a section exhibiting the bottle-neck and stopper shown in 25 Fig. 1, the section being taken transversely through the center of the stopper and the aperture therethrough. Fig. 3 is a plan view of the elastic plug which forms part of my stopper, and Fig. 4 is a section therethrough on 30 line 4 4 of Fig. 3.

In the drawings, A is a bottle-neck which is surrounded by the usual neck-wire a, provided with the usual eyes for the reception of the yoke-lever b, which in turn receives the 35 ends c of the bail-wire, which passes through the aperture d in the plug e, thereby carrying the plug. The plug is provided with a knob e', behind which is a neck e², from which the sides e³ slope away to the body of the plug.

40 This plug is preferably made of porcelain or other hard substance. Porcelain, however, being cheap and incorrodible, is admirably suited for the purpose. The more elastic member of the stopper is constituted by the 45 elastic plug B, which consists of an annular member b', combined with an annular member b² of smaller diameter and smaller annulus, so that the edge b³ of the annulus b' forms a shoulder. This elastic member I preferably 50 make of rubber for reasons of economy and efficiency, and in the present instance have shown it as having its annulus b² of considerably smaller diameter than the bottle-mouth, and its annulus b' of somewhat greater di-

ameter than the bottle-mouth when the plug 55 B is on the plug e, which will be clearly seen by an inspection of Fig. 1. In this figure, as before pointed out, the stopper is shown as about to be entered into the bottle-mouth, while in Fig. 2 the stopper is shown as actually 60 entered.

In Fig. 2 I have clearly shown the form taken by the rubber plug B, whence it will be noted that the bottle-mouth is doubly sealed. First, there is a seal around the mouth between the 65 lines 1 2, which is the primary seal, and the secondary seal around the lips of the mouth, as indicated at 3. So therefore there is not only an internal or inside mouth-seal, but also an external or lip seal. It will also be noted 70 that a very small amount of rubber has been used to effect this double seal and that the stopper will efficiently seal hair-lipped bottles and chipped bottles.

It will be seen that the larger or elastic 75 member b' projects away from the tapered plug above the same and thereby leaves a vacant space between the outer rim or edge of said elastic member and the tapered portion of the said plug. This serves the function 80 of allowing the elastic member to be stretched while being pressed into the bottle-mouth, thereby snugly fitting the tapered portion of the plug and the interior of the bottle-mouth, as is clearly shown in Fig. 2. It also serves the 85 function of great saving in rubber, since by so stretching and compressing the rubber upon the application of the stopper to the bottle the flange b' forms in reality a better 90 interior seal than has heretofore been accomplished by a relatively much larger quantity of rubber.

I am aware that a flanged elastic plug is not new, and I do not mean to be understood as claiming such a plug broadly, but 95

What I do claim, and desire to secure by Letters Patent, is—

A stopper comprising a tapered plug, and a stepped elastic stopper member carried upon the same and leaving a space between the 100 outer edge of the upper and larger stepped portion of said member and said plug, substantially as described and for the purpose set forth.

KARL HUTTER.
